UNITED STATES PATENT OFFICE.

GEORGE RICHARD BAIR, OF TOPEKA, KANSAS, ASSIGNOR OF ONE-THIRD TO SAMUEL ALLEN KINNE AND ONE-THIRD TO JOSEPH MARTIN CATREN, BOTH OF TOPEKA, KANSAS.

OIL-BURNER.

1,034,056.

Specification of Letters Patent. Patented July 30, 1912.

Application filed October 9, 1911. Serial No. 653,532.

To all whom it may concern:

Be it known that I, GEORGE R. BAIR, a citizen of the United States, residing at Topeka, in the county of Shawnee and State 5 of Kansas, have invented a new and useful Oil-Burner, of which the following is a specification.

The invention relates to improvements in oil burners.

10 The object of the present invention is to improve the construction of oil-burners, and to provide a simple, efficient and comparatively inexpensive burner, adapted to be readily applied to stoves, furnaces, locomotives, etc., and capable of using as a fuel either refined or crude oil without danger and without soot, smoke or odor. A further object of the invention is to provide an oil burner of this character, adapted to be used in series with a single source of supply, and capable of enabling one or more burners to be operated.

With these and other objects in view, the invention consists in the construction and 25 novel combination of parts hereinafter fully described, illustrated in the accompanying drawing, and pointed out in the claim here-to appended; it being understood that various changes in the form, proportion, size 30 and minor details of construction, within the scope of the claim, may be resorted to without departing from the spirit or sacrificing any of the advantages of the invention.

35 In the drawing:—Figure 1 is an elevation of a series of oil burners, constructed in accordance with this invention. Fig. 2 is a perspective view of one of the burners. Fig. 3 is a detail sectional view, illustrating the 40 construction of the burner casing.

Like numerals of reference designate corresponding parts in all the figures of the drawing.

In the accompanying drawing in which is 45 illustrated the preferred embodiment of the invention, 1 designates a fuel tank, designed to be arranged in any convenient location either adjacent to or remote from the stove or furnace, and adapted to contain either 50 crude or refined oil and air under pressure, which forces the fuel through a supply pipe 2 having a horizontal branch 3, extending into the fire pot of a stove 4 and equipped at intervals with needle valves 5 for controlling the flow of the fuel to a plurality of

bent vaporizing pipes 6. Each vaporizing pipe 6, which is approximately U-shaped, is composed of upper and lower approximately horizontal arms or portions 7 and 8 and a connecting bend, the upper arm or portion being connected with the needle valve 5 and the lower arm or portion being closed at its terminal and supporting at an intermediate point a burner casing 9. The burner casing 9, which is approximately cylindrical, consists of a horizontal bottom 10 and vertical walls having opposite circular openings 11, through which the lower arm or portion of the vaporizing pipe passes. The lower arm of the vaporizing pipe is arranged at the bottom 10 of the burner casing, which is suitably secured to the vaporizing pipe, and the latter is provided within the burner casing with an outlet 12, located at a point intermediate of its ends and centrally of the casing.

The burner casing is provided at opposite sides adjacent to the bottom with lower air inlet openings 13, and it is equipped with an approximately pyramidal cap 14, having radially arranged rows of perforations 15 at which the gas burns with a blue flame when the burner is in operation. The tapered cap, as clearly shown in Fig. 2 of the drawing, has flat inwardly tapered upper sector-shaped faces forming radial ridges or edges, and the perforations 15 are arranged at intervals along the radial ridges or edges of the upper face of the cap. The burner casing projects upwardly from the lower arm or portion of the vaporizing pipe, and the burner cap 14 is located beneath the upper arm or portion so that the burner heats the said upper arm or portion 7 and vaporizes the oil discharged into the same from the 90 needle valves. The vaporized oil and the mixed air commingle within the burner casing and burn with a blue flame similar to a Bunsen tube. The tapered or conical cap is provided with a depending annular flange 16, which fits within the top of the body of the burner casing.

In order to heat the vaporizing pipe sufficiently to start the burner, the latter is equipped with a cup 17, provided with an 105 arm 18 mounted on a pivot 19, depending from the bottom of the needle valve. The arm 18 is provided with an eye 20 through which the pivot 19 passes, and the receptacle is adapted to be filled with oil and swung 110

beneath the upper arm or portion 7 of the vaporizing pipe for the initial heating of the same. The oil is then lighted and after the vaporizing pipe becomes sufficiently heated to convert the oil into a gas, the burner may be lighted and the pivoted cup or receptacle may then be swung around from beneath the upper arm or portion of the vaporizing pipe, so as to be out of the way of the flame of the burner. The flow of the fuel to the burner is controlled by the needle valve, which regulates the size of the flame when the burner is in operation.

One or more of the burners may be used and either crude or refined oil may be burned with perfect safety, as the fuel under pressure within the supply pipe prevents the flame from entering the same. The burner will operate properly within a stove or furnace, and it is not necessary to provide an air tight closure for the burners.

Having thus fully described my invention, what I claim as new and desire to secure by Letters Patent, is:—

25 A burner of the class described comprising

30 a supply pipe, a bent vaporizing pipe connected therewith and composed of upper and lower approximately horizontal portions and a connecting bend, the lower portion being provided at an intermediate point with an outlet, and an approximately cylindrical burner casing supported in a vertical position by the lower portion of the vaporizing pipe and inclosing the outlet thereof and located beneath the upper portion of the vaporizing pipe, said burner casing being provided at the lower portion with an air inlet and having a substantially pyramidal cap provided with a series of flat sector-shaped faces forming radial ridges or 35 edges, the cap being provided along the ridges or edges with perforations.

35 In testimony, that I claim the foregoing as my own, I have hereto affixed my signature in the presence of two witnesses.

GEORGE RICHARD BAIR.
